SKATE STRAP

Charles E. Jones, Chicago, and William G. Crowle,
Berwyn, Ill.

Application June 2, 1958, Serial No. 51,144

Term of patent 14 years

(Cl. D34—14)

We claim:

The ornamental design for a skate strap, substantially as shown.
